Chappell & Earl

ATTORNEYS

UNITED STATES PATENT OFFICE.

LULU S. SCHROEDER, OF LANSING, MICHIGAN.

ALARM DEVICE.

Application filed April 29, 1922. Serial No. 557,476.

To all whom it may concern:

Be it known that I, LULU S. SCHROEDER, a citizen of the United States, residing at Lansing, county of Ingham, State of Michigan, have invented certain new and useful Improvements in Alarm Devices, of which the following is a specification.

This invention relates to improvements in alarm devices.

10 My improved alarm device is especially designed by me for the use of deaf people, although it is desirable for the use of others as in traveling, or for nurses, and in other instances where a sound alarm is objectionable.

15 The main object of this invention is to provide an improved alarm device which may be attached to the wrist or some other portion of the body and awaken the sleeper by a vibrating or other member coming in contact with the body when actuated by the alarm.

20 Further objects, and objects pertaining to details and economies of construction and 25 operation will definitely appear from the detailed description to follow.

25 I accomplish the objects of the invention by the devices and means described in the following specification. The invention is clearly defined and pointed out in the claim.

30 A structure which is a preferred embodiment of the invention is fully illustrated in the accompanying drawing forming a part of this application, in which:

35 Fig. I is a front view of my improved alarm device.

40 Fig. II is a side view thereof, the same being shown in position on the arm of a person, the housing for the alarm actuated member being partially broken away to disclose the position of the member therein.

45 In the drawings similar numerals of reference refer to similar parts in both views.

Referring to the drawing, the timepiece casing 1 is shown more or less conventionally and the mechanism thereof is not disclosed as timepiece and alarm mechanisms

suitable for the purpose are well-known to watch and clock makers.

The alarm mechanism is provided with 50 an actuated member 2 which projects from the edge of the casing at one side. A housing 3 is provided for this actuated member so that it is not displaced or injured by coming in contact with the clothing or bedding.

The timepiece is mounted upon the straps 4 by means of which it may be attached as to rest on the arm of a person. Thus arranged, when the vibrating member 2 is 60 actuated it strikes or taps the arm, thereby giving the alarm.

While I have designed my alarm especially for the benefit or the use of deaf people, it is very desirable for use by 65 travelers, nurses and the like where sounding alarms are not desirable.

I have illustrated my improvements more or less conventionally as the structural details of the timepiece mechanism form no 70 part of my invention. It is believed, however, that the disclosure made will enable those skilled in the art to which my invention relates to embody or adapt the same as may be desired.

Having thus described my invention, what I claim as new and desire to secure by Letters Patent is:

In an alarm device, the combination of a time piece comprising a casing and an 80 alarm mechanism including a vibrating member actuated by the alarm mechanism and projecting from the edge of the casing to engage the body of the person to whom the device is attached, a housing for said 85 vibrating member open on its under side, and an attaching strap on which the casing is mounted for securing to the body, said casing being mounted on said strap so that said housing lies at one edge of the strap. 90

In witness whereof, I have hereunto set my hand and seal.

LULU S. SCHROEDER. [L. S.]
